B. S. LA FLEUR.
BACK GAGE FOR SHOE SEWING MACHINES.
APPLICATION FILED JUNE 22, 1915.
1,240,985. Patented Sept. 25, 1917.

Inventor:
Benjamin S. LaFleur,
by my son James V. LaFleur,
Attest.

UNITED STATES PATENT OFFICE.

BENJAMIN S. LA FLEUR, OF BEVERLY, MASSACHUSETTS.

BACK-GAGE FOR SHOE-SEWING MACHINES.

Specification of Letters Patent. Patented Sept. 25, 1917.

1,240,985.

Application filed June 22, 1915. Serial No. 35,688.

To all whom it may concern:

Be it known that I, BENJAMIN S. LA FLEUR, a citizen of the United States, and a resident of Beverly, county of Essex, and 5 Commonwealth of Massachusetts, have invented an Improvement in Back-Gages for Shoe-Sewing Machines, of which the following description, in connection with the accompanying drawings is a specification, 10 like characters on the drawings representing like parts.

This invention relates to inseam shoe sewing machines and more particularly to welt and turn shoe sewing machines for sewing 15 welted and turn-work, and the invention has for its object to improve machines of the class referred to.

The objects and features of the invention will best be understood from the following 20 description taken in connection with the accompanying drawings of a welt and turn shoe sewing machine embodying one form of said invention selected for the purpose of illustration, it being understood that the invention in its true scope is definitely set 25 forth by the claims.

Figure 1 is a right-hand side elevation of a sufficient portion of a welt and turn sewing machine, equipped to sew turn-work and 30 embodying the present invention, to enable the invention to be understood;

Fig. 2 is a detail;

Fig. 3 is a detail on an enlarged scale showing my improved back gage, the needle, 35 the channel guide 4 and the work as it contacts with the gage.

Fig. 4 is a top plan view of my improved back gage and of the gage supporting arm; and

Fig. 5 is a sectional side elevation of said back gage and supporting arm.

Fig. 6 is a detail on an enlarged scale showing my improved back gage in operative position in the sewing of a turn shoe.

The invention is herein shown as applied 45 to the welt and turn shoe sewing machine described in United States Patent No. 412,704, of October 8, 1889, but it will be apparent that the invention is equally applicable to other turn shoe sewing machines.

Referring to Fig. 1, the machine is provided with an awl 2, a channel-guide 4, a welt guide slide 6, a thread guide or looper 8, a hooked needle 10, its guide 12, a needle- 50 segment 14, a take-up 16, auxiliary take-up

18, a thread arm, a sliding rest 19, and a tension device, and all of said parts and their actuating mechanisms may and herein have the same general construction, arrangement and mode of operation, except 60 as hereinafter described, as the corresponding parts of the welt and turn machine disclosed in Patent 412,704 above referred to, to which patent reference may be made for a full description of said parts, 65 further description thereof being therefore deemed unnecessary herein. To these parts is added my improved back gage for use on turned work.

As the present invention applies more 70 particularly to turn shoe sewing machines, the usual welt guide is omitted, the improved back gage embodying my invention being herein secured to the end of the welt 75 guide slide 6 in place of said welt guide.

As already stated, said welt guide slide may be operated in the usual manner, it being moved positively in both directions by a lever 20 operated by a suitable cam, Fig. 1, and the slotted link 22 which embraces the 80 screw stud 24 projecting from one side of the welt guide slide 6. A block 26 is placed in the slot of said link 22, said block being provided with a screw stud 28, Fig. 2, by which to adjust and secure said block in 85 the slot of said link, thus shortening or lengthening the slot according as it is desired to shorten or lengthen the throw of the welt guide slide and back gage 7. A spring 30 secured at one end to said lever 20 90 and at the other end to said stud 24 acts normally to keep the slide forward with its pin 32 against an adjustable stop 34, but should said spring for any cause fail to advance the back gage into correct position at 95

the proper time, then the link 22 in its forward movement, preparatory to the entrance of the needle into the work, acts through the stud 24 to carry the welt guide and back gage forward into correct position. After 100 the needle arrives at its lowest position, and while it rises to draw the loop, the welt guide slide 6 is locked in its forward position in well known manner by a pawl 36 which engages for that purpose a toothed 105 block 38 fast on the welt guide slide 6, said pawl 36 being controlled by a lever 40 actuated by a suitable cam, a spring 42 tending to maintain said pawl in engagement 110 with the toothed block 38.

In the embodiment of the invention herein shown and described, my novel back gage 7 for use in operating upon turn-work is mounted upon an arm 44 bolted or otherwise rigidly secured to the welt guide slide 6, as more clearly shown in Fig. 1. Said back gage is freely movable relative to its supporting member or arm 44 and to that end, said gage, in the embodiment thereof herein disclosed, consists of a wheel or disk 46 mounted for free rotation upon a screw stud 48 fast in the free end of the supporting arm 44, as shown in Fig. 4. Preferably, the disk 46 will be capable of a certain amount of play upon the stud 48 to enable it to move somewhat transversely to its plane of rotation. The upper and lower surfaces of the disk will preferably be concave, as shown at 50 and 52, and the peripheral surface of said disk 46 will also preferably be concave, said disk being of somewhat greater diameter at its top than at its bottom, so as to cause the upper edge of said peripheral surface to project somewhat beyond the lower edge thereof.

In operation, my novel gage engages the edge of the shoe, that is to say, the lining 56 or upper 58, with its peripheral surface substantially where they extend over the outer edge of the sole. As the work progresses, the gage can rotate freely, thus eliminating friction between the gage and the work, and said gage can also move transversely to the plane of the sole to adapt itself to any irregularities in the sole, upper or lining. The operation of sewing turn shoes is thus greatly facilitated. Heretofore, in sewing turn shoes, the sole had previously to pass through an operation known as "crimping", whereby the edge of the sole was molded or bent downwardly so as to assure that in the subsequent sewing operation the needle would penetrate the upper and sole at the required distance from the edge of the sole, and not at or too close to the edge of the latter. My improved gage does away with the "crimping" operation, that is to say, no prior preparation of the sole in the stock room is necessary, it being possible when using my improved gage, to stitch the upper and lining to the soles of turn shoes just as they come from the chandler, for the reason that the projecting flange at the top edge of the disk 7 bends the sole down as the work proceeds and prevents the needle from striking the edge of the sole and from penetrating the upper at the wrong place, the needle always entering the upper and the sole at a sufficient distance inwardly from the edge of the latter. Furthermore, the use of my improved gage by thus eliminating the "crimping" operation, enables the "beating out" operation, to which the soles of turn shoes were heretofore necessarily subjected after the sole had been

stitched or sewed to the upper, also to be practically done away with, or in any event greatly shortened, since this "beating out" operation, as is well known to those skilled in the art, is largely for the purpose of taking out of the sole the crimp produced therein by the "crimping" operation. It will thus be seen that by using my improved gage in stitching turn shoes, two operations heretofore necessary in making turn shoes are eliminated.

By making the upper surface of the gage concave, the needle in its normal operation is afforded a free and unimpeded path of movement. The back gages of the construction and mode of operation heretofore used to sew turn shoes had the disadvantage that when brought into contact with the work they tended to push the upper and edge of the sole upwardly, thus causing the needle to penetrate the upper and sole in too close proximity to the upper edge of the sole as the latter was held in sewing position, or even between the upper and lower edge of the sole as the work was held in position in the machine. As a result, the sewing was very irregular and the appearance of the finished shoe was greatly impaired, the stitches being visible in the completed shoe and the upper not infrequently being lacerated. As a result also the work was greatly weakened. This was apt to occur even with a perfectly normal needle and still more frequently when the needle was sprung or deviated from its regular path for any other reason. Such a result is impossible when my improved gage is used, for the reason that as the upper edge of my gage overlaps the edge of the sole, the latter is protected from penetration for a certain distance from its edge inwardly, by the needle, even in case the latter, owing to its being sprung or for any other reason, would tend to penetrate the sole too close to the edge of the latter, since such a needle would necessarily in its penetrating movement encounter the upper concave surface of the gage and could not penetrate the upper until its point had passed or slid over the edge of the gage. Ripping of soles and uppers by the needle is thus precluded and my improved gage provides for the penetration of the work along a line at a substantially uniform distance from the edge of the work.

Owing to the disadvantages just pointed out attaching to the use of back gages heretofore constructed and operated, the operators were obliged to watch the work very closely, whereby the work was materially slowed up. To meet this difficulty, the operators generally adopted the expedient of setting the gage back so that it would not contact with the work except during the sewing of such portions of the work where the use of the gage was absolutely essential, as

when sewing around the toe of the shoe. As a result, the operator was without the aid of a back gage during the major portion of the sewing operation and had to regulate 5 and control the sewing operation entirely by the eye and guide the shoe entirely by hand. To turn out good work under these conditions required an expert and really rapid work was impossible. As pointed out 10 in the preceding paragraph, the disadvantages attending the use of back gages as heretofore constructed and operated are overcome when my improved gage is used, so that my gage can be used in sewing all 15 parts of the shoe and the operator is thus not obliged to watch the work as closely. Much more rapid work can thus be done when using my improved gage and an operator of ordinary ability can in a short time 20 turn out more work than could an expert under former conditions.

It will be seen that, as the gage presses the marginal portion of the sole downwardly at the point where and as the needle enters the 25 upper surface of said marginal portion of the sole, the point at which the needle enters the sole is lowered, so that the curved needle in its upward swing along its curved path of movement is caused to emerge at substantially the bottom of the channel. The stitch 30 is thus located in the widest portion of the between substance, thus adding to the strength of the seam as the stitches are much less liable to tear through.

35 As already stated, my improved gage can yield vertically when struck by the needle, whereby breakage of needles, even when the latter are sprung, is practically avoided.

By making the under surface of the gage 40 concave substantially as shown at 52, Fig. 4, I allow for wax, and all clogging by wax, etc., is precluded.

My improved gage offers other advantages besides those above set forth, all of 45 which will readily suggest themselves to those skilled in the art.

My improved gage is moved toward and from the work at the proper times during the operation of the machine by the slide 6, 50 said slide and its actuating mechanism being constructed and operating as previously stated in all respects substantially as in United States Patent 412,704, above referred to and in United States Patent 317,759, and 55 so need not herein be further specifically described. It will be apparent to those skilled in the art that while herein my improved gage is shown as operated by the actuating mechanism disclosed in the two United

60 States patents above referred to, said gage could be operated with equal advantage by any other suitable actuating mechanism, such for example as the welt gage operating mechanism disclosed in United States Pat- 65 ent 1,108,560 and it is to be understood,

therefore, that my invention is not to be considered as limited in any way, shape or manner to any specific actuating mechanism.

It will be apparent that while the invention has herein been described as embodied 70 in the details illustrated, the invention is not to be considered as circumscribed or limited to these details, or any of them, since they may be variously modified within the true scope of the invention which is definitely set 75 forth by the claims.

Claims.

1. In a turn shoe sewing machine, in combination, a gage carrying member; a gage carried by said member and provided with a 80 work engaging surface to be engaged by the edge of the shoe as the latter is held in position to be sewed on the machine, said gage being movable relatively to said member, transversely to the plane of the sole of the 85 shoe to be sewed; and mechanism to move said gage carrying member to bring the gage into operative position.

2. In a turn shoe sewing machine, in combination, a gage carrying member; a gage 90 mounted for rotation on said member and for movement transversely to its plane of rotation; a concave work engaging surface provided on said gage; and mechanism to move said gage carrying member to bring 95 the gage with its work engaging surface into operative position to be engaged by the edge of the shoe as the latter is held in position to be sewed on the machine.

3. In a shoe sewing machine, the combination of a curved needle arranged to pierce the shoe from the outside and emerge from a channel in the shoe sole; and a rotary gage 100 provided with a work engaging surface to engage the edge of the shoe and extend inwardly over the edge of the sole, as the shoe 105 is held in position to be sewed on the machine, and press the marginal portion of the sole downwardly relatively to the rest of the sole at the point where and as the needle penetrates said marginal portion.

4. In a shoe sewing machine, the combination of a curved needle arranged to pierce the shoe from the outside and emerge from a channel in the shoe sole; and a gage rotatable in the direction of feed of the shoe and provided with a peripheral work engaging surface adapted to engage the edge of the shoe and to extend inwardly over the edge of the sole, as the shoe is held in position to be 115 sewed on the machine, and press the marginal portion of the sole downwardly relatively to the rest of the sole at the point where and as the needle penetrates the sole, to cause the needle to pierce the marginal portion of the sole at a point inwardly from the edge of the sole and to emerge in the channel substantially at the base of the latter.

5. In a shoe sewing machine, the combina- 130

- tion of a curved needle arranged to pierce the shoe from the outside and emerge from a channel in the shoe sole; and a rotary gage provided with a work engaging surface 5 adapted to engage the edge of the shoe and to extend inwardly over the edge of the sole, as the shoe is held in position to be sewed on the machine, and press the marginal portion of the sole downwardly relatively to the rest 10 of the sole at the point where and as the needle penetrates the sole, so as to cause the needle to enter the marginal portion of the sole at a point inwardly from the edge thereof and to emerge substantially at the bottom 15 of the channel.
6. In a shoe sewing machine, the combination of a curved needle arranged to pierce the shoe from the outside and emerge from a channel in the shoe sole; and a rotary gage 20 provided with a concave work engaging surface to engage the edge of the shoe and extend inwardly over the edge of the sole, as the shoe is held in position to be sewed on the machine, and press the marginal portion 25 of the sole downwardly relatively to the rest of the sole at the point where and as the needle penetrates said marginal portion, said gage being shaped at its under surface to prevent the accumulation of wax thereon.
7. In a turn shoe sewing machine, in combination, a curved needle arranged to pierce the shoe from the outside and emerge from a channel in the shoe sole; a rotary gage provided with a concave, peripheral, work 35 engaging surface; a gage supporting member; and actuating mechanism for said member to move the gage into position to cause its work engaging surface to be engaged by the edge of the shoe and extend inwardly 40 over the edge of the sole and press the marginal portion of the sole downwardly relatively to the rest of the sole at the point where and as the needle penetrates said marginal portion, as the shoe is presented in position to be sewed on the machine.
8. In a shoe sewing machine, the combination with a curved needle arranged to pierce the shoe from the outside and emerge 50 from a channel in the shoe sole, of the rotary gage 7 provided with the work engaging surface 46 shaped to engage the edge of the sole and to extend inwardly over the edge of the sole and press the latter downwardly at the point where and as the needle 55 penetrates the sole, as the shoe is held in position to be sewed on the machine.

9. In a shoe sewing machine, the combination with a curved needle arranged to pierce the shoe from the outside and emerge from a channel in the shoe sole, of the rotary 60 gage 7 having the upper concave surface 50 and the peripheral work engaging surface 46 shaped to engage the edge of the sole and to extend inwardly over the edge of the sole and press the latter downwardly 65 at the point where and as the needle penetrates the sole, as the shoe is held in position to be sewed on the machine.

10. In a shoe sewing machine, the combination with a curved needle arranged to 70 pierce the shoe from the outside and emerge from a channel in the shoe sole, of the rotary gage 7 having the lower concave surface 52 and the peripheral work engaging surface 46 shaped to engage the edge of the 75 sole and to extend inwardly over the edge of the sole and press the latter downwardly at the point where and as the needle penetrates the sole, as the shoe is held in position to be sewed on the machine.

11. In a shoe sewing machine, the combination of a curved needle arranged to pierce the shoe from the outside and emerge from a channel in the sole; and a gage mounted to yield transversely of the plane of the sole 85 and provided with a surface to engage the edge of the shoe and having its edge extending inwardly over the edge of the marginal portion of the sole as the shoe is held in position to be sewed on the machine, and press 90 the marginal portion of the sole downwardly at the point where and as the needle penetrates said marginal portion, said gage being also provided with a portion to be engaged by the needle in its forward stroke and guide 95 its point into engagement with the upper surface of the marginal portion of the sole at a point inwardly from its edge.

12. In a turn shoe sewing machine, in combination, a gage carrying member; a 100 gage mounted for rotation on said member and movable transversely to its plane of rotation; and a concave work engaging surface provided on said gage.

In testimony whereof, I have signed my 105 name to this specification, in the presence of two subscribing witnesses.
